11 Claims. (Cl. 260—558)

1

This invention relates to a new group of amides of N-arylanthranilic acids and, particularly, to the basically substituted *o*-arylaminobenzamides of the structural formula

and the non-toxic salts thereof, wherein Ar is an aryl radical, Alk is a lower alkylene radical separating the two nitrogen atoms attached thereto by at least two carbon atoms, and NRR' is either a lower dialkylamino radical or a nitrogen containing heterocyclic radical attached through a nitrogen in the heterocycle to the radical Alk.

In the above structural formula Ar is a lower aryl radical and, preferably, a monocyclic aromatic hydrocarbon radical such as phenyl, tolyl, xylyl, ethylphenyl, or cumyl. The radical Alk is a straight-chained or branch-chained hydrocarbon radical such as ethylene, propylene, butylene, amylene, or a polymethylene radical such as trimethylene or octamethylene. The radicals R and R' are lower alkyl radicals of the straight-chained or branch-chained type such as methyl, ethyl, propyl, butyl, amyl, and hexyl. The radicals R and R' can also be combined to form a lower alkylene radical containing 4 to 7 carbon atoms, 4 to 5 of which are in nuclear position as in the case of pyrrolidino, piperidino, 2,5-dimethylpyrrolidino, and 2,6-lupetidino radicals. They may also be combined as an ethyleneoxyethylene radical, ethylenethiaethylene radical, or ethyleneaminoethylene radical as in the cases of the morpholino, thiamorpholino and piperazine radicals.

The bases described herein form salts which are non-toxic in therapeutic dosage with a variety of inorganic and strong organic acids such as phosphoric, hydrochloric, hydrobromic, hydroiodic, sulfamic, acetic, maleic, malic, succinic, tartaric, citric, ascorbic gluconic, benzoic, cinnamic, or related acids. They also form quaternary ammonium salts with a variety of organic esters of sulfuric, hydrohalic, and aromatic sulfonic acids. Among such esters are methyl chloride, bromide, and iodide; the ethyl halides, propyl halides, butyl halides, isobutyl halides, benzyl halides, phenethyl halides, naphthylmethyl halides, dimethyl sulfate, methyl benzenesulfonate, ethyl toluenesulfonate, ethylene chlorohydrin, ethylene bromohydrin, the propylene halohydrins, allyl chloride, methallyl bromide, and crotyl bromide.

2

The new group of amides described herein offers valuable intermediates in organic synthesis. These amides have shown valuable cardiovascular and specifically blood pressure reducing properties. The acid addition salts are diuretics and the quaternary ammonium salts have been found to be potent ganglion blocking agents.

The examples below illustrate my invention in further detail. However, they are not to be construed as limiting it in spirit or in scope. In these examples quantities of materials are given in parts by weight, temperatures in degrees centigrade (° C.), and pressures in millimeters (mm.) of mercury.

EXAMPLE 1

N-(β-diethylaminoethyl)-o-anilinobenzamide

20 A mixture of 426 parts of N-phenylanthranilic acid, 1100 parts of anhydrous ethyl ether, and 272 parts of thionyl chloride is heated in a water bath at 40° C. for one hour. The ether is then removed under vacuum at room temperature and the crude acid chloride residue is used in the reactions with the dialkylaminoalkylamines.

25 To a solution of the above residue in 1600 parts of acetone, 232 parts of β -diethylaminoethylamine are added by dropwise addition, with stirring.

30 After the addition the reaction mixture is refluxed on the steam bath for an hour. The acetone is removed under vacuum and the residue is dissolved in water and ether extracted.

The aqueous phase is made alkaline with potassium carbonate and ether extracted.

35 The ether extract is dried over anhydrous potassium carbonate, ether stripped, and vacuum distilled.

The *N*-(β -diethylaminoethyl)-o-anilinobenzamide is a viscous, orange oil boiling at approximately 221–227° C. and 0.5 mm. pressure.

40 To a solution of 280 parts of the base in 11,000 parts of anhydrous ethyl ether, one equivalent of a 25% solution of hydrogen chloride in isopropanol is added. A brown gum separates which, after three recrystallizations from butanone, is converted to a tan-colored crystalline powder melting at 163–164° C. This salt has the structural formula

45

3
EXAMPLE 2

β-(o-anilinobenzamidoethyl) triethylammonium bromide

A mixture of 110 parts of N-(β -diethylaminoethyl)-o-anilinobenzamide, 76 parts of ethyl bromide, and 1600 parts of butanone is sealed in a pressure bottle and heated in the steam bath for 3 hours. Observing the usual precautions, the pressure bottle is cooled and opened. A heavy syrup is separated from the reaction mixture by dilution with anhydrous ethyl ether. The syrup is washed by ether decantation, taken up in acetone, and crystallized by cooling in the refrigerator. Two recrystallizations from acetone and vacuum drying yield pale yellow crystals of the β -(o-anilinobenzamidoethyl)triethylammonium bromide which are too hygroscopic for the determination of a sharp melting point. The salt has the structural formula

EXAMPLE 3

N-(γ-dimethylaminopropyl)-o-anilinobenzamide

To the acid chloride residue prepared from 41 parts of N-phenylanthranilic acid, a solution of 20 parts of γ -dimethylaminopropylamine in 100 parts of acetone is added slowly with stirring. After heating at reflux temperature for an hour the acetone is distilled off under vacuum and the residue is dissolved in water. The aqueous extract is washed with ether, rendered alkaline by addition of potassium carbonate, and ether extracted. This ether extract is dried over anhydrous potassium carbonate, solvent stripped, and vacuum distilled to yield the N-(γ -dimethylaminopropyl)-o-anilinobenzamide as a viscous yellow oil boiling at about 223-230° C. and 0.3 mm. pressure.

To a solution of 9.5 parts of the base in 1400 parts of anhydrous ethyl ether is added one equivalent of a 25% solution of hydrogen chloride in isopropanol. The resultant granular pink precipitate is filtered, ether washed, and vacuum dried under an infrared lamp. Drying transforms the precipitate to a red gum. The latter is taken up to 40 parts of butanone from which it rapidly crystallizes. After one recrystallization from butanone a white, non-hygroscopic crystalline powder is obtained which melts at 133-135° C. This salt has the structural formula

4
EXAMPLE 4

N-(γ-diethylaminopropyl)-o-anilinobenzamide

To the acid chloride residue prepared from 5 318 parts of N-phenylanthranilic acid is added, with stirring, a solution of 195 parts of γ -diethylaminopropylamine in 1000 parts of acetone. The addition causes refluxing which is maintained for one hour by heating on the steam bath. The acetone is removed under vacuum and the residue is dissolved in water and ether washed. The aqueous phase is made alkaline with potassium carbonate and ether extracted. This ether extract is dried over anhydrous potassium carbonate, ether stripped and vacuum distilled. The N-(γ -diethylaminopropyl)-o-anilinobenzamide is a viscous yellow oil boiling at about 220-230° C. and 0.3 mm. pressure.

To a solution of 60 parts of the base in 14,000 parts of anhydrous ethyl ether, an equivalent of 20 a 25% solution of hydrogen chloride in isopropanol is added. The hydrochloride precipitates as a tacky deposit which becomes a crystalline powder on standing and scratching. Filtration and vacuum drying under an infrared lamp yield 25 a cream colored, non-hygroscopic powder, melting at about 97-103° C. The salt has the structural formula

EXAMPLE 5

N-(β-dimethylaminopropyl)-o-(m,p-xylyl)aminobenzamide

The acid chloride residue prepared from 41 45 72 parts of N-(m,p-xylyl)anthranilic acid is treated by dropwise addition with a solution of 31 parts of β -dimethylaminopropylamine in 150 parts of acetone. After heating at reflux temperature for 90 minutes the solvent is removed under vacuum. The residue is dissolved in water and the resulting solution washed with ether, rendered alkaline by addition of potassium carbonate, and ether extracted. This extract is dried over anhydrous potassium carbonate, filtered, and concentrated under vacuum. The N-(β -dimethylaminopropyl)-o-(m,p-xylyl)aminobenzamide is distilled at about 255-265° C. and 0.5 mm. pressure. It has the structural formula

EXAMPLE 6

N-(ω-diethylaminopentyl)-o-anilinobenzamide

A solution of phenylanthranilic acid chloride, prepared from 135 parts of the acid in 500 parts 75 of acetone, is treated with stirring by the gradual

5

addition of 100 parts of ω -diethylaminoethylpentylamine. After heating at reflux temperature for an hour, the solvent is removed under vacuum and the residue is dissolved in water. The aqueous extract is ether washed, made alkaline by addition of potassium carbonate, and ether extracted. The ether extract is dried over anhydrous potassium carbonate, filtered, and evaporated. The N -(ω -diethylaminopentyl)- ω -anilinobenzamide is obtained by vacuum distillation at about 256-264° C. and 0.5 mm. pressure as a viscous yellow oil. It can be crystallized from petroleum ether. The compound has the structural formula

I claim:

1. A member of the class consisting of the compounds of the structural formula

and the salts of the structural formula

wherein Ar is a monocyclic hydrocarbon radical containing 6 to 9 carbon atoms, Alk is a lower alkylene radical separating the two nitrogen atoms attached thereto by at least 2 carbon atoms and X is a non-toxic anion.

2. A compound of the structural formula

wherein Alk is a lower alkylene radical separating the two nitrogen atoms attached thereto by at least two carbon atoms.

3. A compound of the structural formula

wherein Alk is a lower alkylene radical separating the two nitrogen atoms attached thereto by at least two carbon atoms.

4. A compound of the structural formula

6

5. A compound of the structural formula

wherein Alk is a lower alkylene radical separating the two nitrogen atoms attached thereto by at least two carbon atoms.

6. A compound of the structural formula

7. A compound of the structural formula

8. A compound of the structural formula

9. A salt of the structural formula

wherein Alk is a lower alkylene radical separating the two nitrogen atoms attached thereto by at least two carbon atoms, and X is a non-toxic anion.

10. A salt of the structural formula

wherein Alk is a lower alkylene radical separating the two nitrogen atoms attached thereto by at least two carbon atoms.

11. A salt of the structural formula

CARL PETER KRIMMEL.
